UNITED STATES PATENT OFFICE.

CHARLES ALGERNON PARSONS, OF NEWCASTLE-UPON-TYNE, AND STANLEY SMITH COOK, OF WALLSEND-UPON-TYNE, ENGLAND; SAID COOK ASSIGNOR TO SAID PARSONS.

TURBINE.

986,749.

Specification of Letters Patent. Patented Mar. 14, 1911.

Application filed July 9, 1910. Serial No. 571,214.

To all whom it may concern:

Be it known that we, CHARLES ALGERNON PARSONS, C. B., a subject of the King of Great Britain and Ireland, and residing at 5 Heaton Works, Newcastle-upon-Tyne, in the county of Northumberland, and STANLEY SMITH COOK, a subject of the King of Great Britain and Ireland, and residing at Turbinia Works, Wallsend-upon-Tyne, in the 10 county of Northumberland, England, have invented certain new and useful Improvements in and Relating to Turbines, of which the following is a specification.

This invention relates to compound turbines of the type in which the steam is allowed to flow through a segmental portion only of the annulus between the wheel carrying the rotating blades and the casing carrying the fixed blades and in which the 20 velocity of the steam through the successive rows of guide blades and rotating blades is maintained chiefly or entirely by dropping pressure small amounts at a time, as occurs for instance in the well known Parsons' 25 type of blading, these small drops of pressure occurring in either or in both the fixed guide blades and rotating blades. Such turbines may conveniently be said to be of the "partial impingement with fractional 30 conversion of pressure" type.

Various turbines of this character are described in our Patents Nos. 28047/1907, 17872/1908 (in the complete specification of which is cognate the provisional 35 specification No. 28374/1908); 28373/1908, 28375/1908 and 28376/1908.

In turbines of the above character it is usual to provide short end blockings or stops at each end of the sectors of guide 40 blades in order to prevent leakage of steam in a circumferential direction. These blockings are adapted to extend as close to the rings of rotating blades as is possible; they are also continued for a short distance only 45 on each side of the sectors of guide blades so as to avoid loss due to skin friction between the rotating rings of blades and the blockings. From its point of exit from the short end blockings on one side of a sector 50 of guide blades or impingement zone, to its entrance between the short end blockings on the other side of the same impingement zone or between the blockings on one side of another impingement zone, the rotating 55 blades run in a chamber filled with steam

at a pressure above or below that existing in the impingement zone from which they are issuing or into which they are about to enter. In turbines of this character there has therefore been hitherto an unavoidable 60 loss owing to a volume of steam being held between the rotating blades and carried from a place of one pressure to a place where a lower pressure exists, a certain quantity of steam being thus transferred from a place 65 of higher density to a place of lower density without doing any work.

The object of the present invention is to prevent the loss hitherto occasioned by the transference of the volume of steam held in 70 the rotating blades.

The invention consists broadly in withdrawing steam from the rotating blades during their passage through one set of short end blockings and delivering it to the 75 blades when passing through another set of short end blockings whereby increased economy is obtained.

The invention also consists for this purpose in connecting the spaces between adjacent short end blockings on one side of an impingement zone by means of one or more passages with the spaces between adjacent short end blockings on the other side of the same impingement zone. By this means 80 when the pressure of the steam in the impingement zone is higher than the pressure existing in the chamber, part of the volume of dense steam, held between the rotating blades, and which would otherwise enter 85 the chamber, is transferred through this passage and caused to fill up the blades which are running into the impingement zone from the chamber where the lower pressure exists. In the case when the impingement zone is at a lower pressure than the chamber, part of the volume of denser steam, held in the rotating blades about to enter the impingement zone, is transferred 90 through this passage and caused to enter 95 the blades again as they leave the impingement zone and are about to reenter the chamber. Thus a certain amount of steam, which would otherwise be carried over from the impingement zone into the lower pressure chamber or from the chamber into a lower pressure impingement zone and consequently lost, is being continuously restored to the part of higher pressure.

It is obvious that a passage may be pro- 110

vided for every pair of corresponding short end blockings or they may only be provided where the difference of pressure between the impingement zone and the chamber is greatest. In some cases it may be preferable to provide two or more such passages where this pressure difference is greatest and only one where the pressure difference is less. The transference of steam from the blades 10 entering the impingement zone to the blades leaving this zone, or conversely, is thus effected at various points successively intermediate between the pressure in the impingement zone and the pressure in the 15 chamber in which the wheel is situated and the leakage of steam into or from which it is desired to diminish.

It is preferable that the end of a passage receiving the steam from the rotating blades 20 should be expanded in order to facilitate the outflow of steam from the blades into the passage, and also that the end delivering steam to the blades should be restricted so as to give a slightly increased velocity to the 25 steam to facilitate its inflow into the blades, and to avoid any retarding effect as the steam strikes these blades. If the openings of these connecting passages are formed oblique to agree with the direction of rotation 30 of the rotating blades, the entry and exit of the steam to and from the blades and passages is also facilitated.

The invention also consists in the arrangements of connecting passages as hereinafter indicated.

Referring now to the accompanying drawings which are diagrammatic only:—Figure 1 is a part longitudinal section on the line B—B of Fig. 2, of a turbine according to the 40 present invention. Fig. 2 is a part transverse section on the line A—A of Fig. 1. Fig. 3 is an inverted developed view on the line D—E—F of Fig. 2. Figs. 4 and 5 are part views similar to Figs. 1 and 2; showing 45 a modification of the invention. Figs. 6—16 show further modifications.

In carrying this invention into effect for instance as shown in Figs. 1, 2 and 3, in a turbine in which the steam flows in one direction through one series of guide blades *a* and rotating blades *b* and is then discharged into a chamber *c* from which it passes by means of a second series of guide blades *a* in the same direction to its exit from the 55 chamber, we arrange one or more passages *e* connecting the short end blockings *f* on each side of the same sector of guide blades. The passages *e* as shown in Figs. 1 and 2, are formed completely in a separate member *g* which is secured by bolts *h*, as shown or otherwise fastened to the turbine casing *i*, and which carries the guide blades *a* and short end blockings *f* the passages *e* in this member *g* being arranged to open into the 60 space between the adjacent short end block- 65

ings. As shown in Figs. 1 to 3, the space between the short end blockings *f* at the ends of adjacent sectors of guide blades are connected by a single passage *e*. Obviously however two or more such passages may be used if the pressure difference between the impingement zone and the chamber be very great.

Figs. 4 and 5 show a modification in which two passages *e* are provided, one set 75 of such passages are formed in a member *g* as in the previous modification, while the second set are formed as grooves in this member which grooves are closed by the casing *i* when the member *g* is in position. 80 In some cases such as where the pressure in the impingement zone is very near to the pressure in the chamber *c* we may omit the passages *e* and only connect the short end blockings *f* where the pressure difference is 85 higher. In other cases instead of providing two passages over the whole length of the impingement zone as shown in Figs. 4 and 5 we may arrange two passages at the commencement of the impingement zone, where the pressure difference is greater and only one passage where the difference between the pressure in the zone and the pressure in the chamber is less.

Various other methods of forming the 95 connecting passages *e* are shown in Figs. 6 to 16. For instance, as shown in Figs. 6 and 7, the passages *e*, are formed in the body of the casing *i* itself while in Figs. 8 and 9, the passages are shown formed by grooves 100 in the internal face of the turbine casing *i* these grooves being closed by the member *g* on which the guide blades are mounted.

In a further construction shown in Figs. 10 and 11, holes *m* through the turbine casing *i* are provided and the passages *e* are 105 formed by grooves in a member *k* securely fastened to the exterior of the casing *i* the grooves being adapted to register with the holes *m*. In Figs. 12 and 13 a modification 110 of this last arrangement is shown in which the passages *e* are formed entirely in a member *n* secured to the turbine casing *i* while in Figs. 14 and 15 two sets of passages *e* are 115 shown formed in such a member *n*.

The arrangement shown in Figs. 8 and 9 may be modified by forming the grooves in the member *g* these grooves being closed by the turbine casing *i* as shown in connection with one of the sets of passages in Figs. 4 and 5. In the case in which two or more passages are provided over the whole or only part of the length of the impingement zone, we may form some of these passages in the body of the turbine casing itself and some in a member attached to the exterior of the casing in the manner already explained or we may arrange that both these passages shall be formed in the body of the casing itself. In such cases in fact we may 125 130

arrange the passages partly in one and partly in another of the methods already referred to. For instance as shown in Fig. 16, one set of passages *e* which extend the whole length of the impingement zone are formed in the blade carrying member *g* while the second set of passages *e* which extend over only the first part of the impingement zone are formed by grooves in 10 the turbine casing *i* which are closed by the member *g*.

As shown in all the modifications, we preferably form the ends of the passages *e* oblique to agree with the direction of rotation 15 of the moving blades, *b* and restrict the end of the passage delivering the steam to the blades in order to give a slight increase of velocity to the steam to facilitate its inflow into the blades and to prevent any retarding effect that the steam might have when 20 entering the blades. Also the end of the passage receiving the steam from the blades is expanded so as to facilitate the outflow of steam from these blades. Any other 25 convenient method of forming the passages between the short end blockings may be used, and we do not in any way limit our invention to the particular arrangements herein described and shown.

30 In a turbine of the kind shown in Figs. 1-3 in which the steam flows twice in the same direction through the rings of rotating blades *b* it will be seen that the rotating blades which are moving in the direction of 35 the arrow 1, will as they leave the first impingement zone *o* give up part of the dense steam with which they are filled before they enter into the chamber *c* which is filled with steam of lower density. This steam will be 40 transferred through the passage *e* and delivered into the rotating blades *b* as they pass from the chamber *c* into the same impingement zone *o*. In the second impingement zone *p* where the steam passes from 45 the chamber *c* through the blades before passing into another part of the turbine it will be seen that the rotating blades *b* that are about to enter the impingement zone *p* are filled with steam at a higher pressure 50 than that which actually exists in such impingement zone. By means of the passages *e* however, part of this steam is by-passed across the impingement zone *p* and is delivered into the rotating blades *b* as they 55 are about to pass from the lower pressure of the impingement zone *p* into the higher pressure chamber *c*. Thus in both these cases a certain amount of steam which would otherwise be carried from the higher 60 pressure of the impingement zone *o* to the lower pressure of the chamber *c* and from the higher pressure of the chamber *c* into the lower pressure of the impingement zone *p* and consequently lost, is being continuously restored to the part of higher pres-

sure. The transference of steam from the blades entering the impingement zone to the blades leaving the zone or conversely, it will be seen, is effected at various points successively intermediate between the pressure in the impingement zone and the pressure in the chamber in which the wheel is situated and the leakage of steam into or from which it is desired to diminish.

70 This invention may be applied to any of the turbines made in accordance with our patents as above numbered or to any turbine in which a fractional conversion of the pressure of the steam is effected, with partial impingement of the rings of rotating 80 blades, no matter whether such rotating blades are of the "Parsons" or "crescent" formation. It is thus applicable to all partial impingement turbines of the reaction type and also to those of the type in which 85 the conversion of pressure into velocity takes place in fixed guide blades only, the velocity energy being transformed into mechanical energy on the rotating blades.

90 It will be seen that the method of carrying this invention into effect is capable of various modifications without in any way affecting the spirit of the same.

95 Having now described our invention what we claim as new and desire to secure by Letters Patent is:—

1. In combination with a turbine having partial impingement with fractional conversion of the pressure energy of the working fluid into kinetic energy, means for passing 100 working fluid from one impingement zone boundary to another such boundary.

2. In combination with a turbine having partial impingement with fractional conversion of the pressure energy of the working 105 fluid into kinetic energy, means for passing working fluid from the boundary on one side of an impingement zone to the boundary on the other side of the same zone.

3. In combination with a turbine having 110 partial impingement of the working blades with fractional conversion of the pressure energy of the working fluid into kinetic energy, means for receiving working fluid from the blades at one impingement zone boundary and for delivering the fluid so received 115 into the blades at another such boundary.

4. In combination with a turbine having partial impingement of the working blades with fractional conversion of the pressure 120 energy of the working fluid into kinetic energy, means for receiving steam from said working blades on one side of an impingement zone and for delivering the same into the working blades on the other side of said 125 zone.

5. In combination with a turbine having partial impingement with fractional conversion of the pressure energy of the working 130 fluid into kinetic energy, short end blockings

- on each side of an impingement zone and means for passing working fluid from one set of such blockings to another set.
6. In combination with a turbine having partial impingement of the working blades with fractional conversion of the pressure energy of the working fluid into kinetic energy, short end blockings on each side of an impingement zone, means for receiving working fluid from said blades when passing between one set of said blockings and for delivering the same into said blades on their passage through another set of short end blockings.
- 15 7. In combination with a turbine having partial impingement of the working blades with fractional conversion of the pressure energy of the working fluid into kinetic energy, passages for passing working fluid from one impingement zone boundary to another such boundary.
- 25 8. In combination with a turbine having partial impingement of the working blades with fractional conversion of the pressure energy of the working fluid into kinetic energy, passages for passing working fluid from one impingement zone boundary to another such boundary, the ends of said passages being inclined in the direction of rotation of the working blades.
- 35 9. In combination with a turbine having partial impingement of the working blades with fractional conversion of the pressure energy of the working fluid into kinetic energy, passages adapted to receive working fluid from the working blades at one impingement zone boundary and to deliver the fluid so received into the blades at another such boundary.
- 40 10. In combination with a turbine having partial impingement of the working blades with fractional conversion of the pressure energy of the working fluid into kinetic energy, passages adapted to receive working fluid from the working blades at one impingement zone boundary and to deliver the fluid so received into the blades at another such boundary, the ends of said passages being inclined in the direction of rotation of the working blades.
- 45 11. In combination with a turbine having partial impingement of the working blades with fractional conversion of the pressure energy of the working fluid into kinetic energy, passages for passing working fluid from one impingement zone boundary to another such boundary, said passages at their receiving ends being expanded and at their delivery ends being restricted in cross sectional area, said ends being inclined in the direction of rotation of the working blades.
- 55 12. In combination with a turbine having partial impingement of the working blades with fractional conversion of the pressure energy of the working fluid into kinetic energy,
- 60 13. In combination with a turbine having partial impingement of the working blades with fractional conversion of the pressure energy of the working fluid into kinetic energy, passages adapted to receive working fluid from said blades on one side of an impingement zone and to deliver the same into the working blades on the other side of said zone, said passages at their receiving ends being expanded and at their delivery ends being restricted in cross sectional area, said ends being inclined in the direction of rotation of the working blades.
- 65 14. In combination with a turbine having partial impingement with fractional conversion of the pressure energy of the working fluid into kinetic energy, short end blockings on each side of an impingement zone, passages adapted to receive working fluid from said blades when passing between one set of said blockings, and to deliver the same into said blades on their passage through another set of such blockings, said passages at their receiving ends being expanded and at their delivery ends being restricted in cross sectional area, said ends being inclined in the direction of rotation of the working blades.
- 70 15. A turbine comprising in combination stationary elements co-acting with rotating vanes fractionally to convert the thermal energy of the working fluid into useful work, said stationary elements only partly extending over said rotating vanes to form impingement zone or zones, and means for receiving working fluid from said rotating vanes at one impingement zone boundary and for delivering the fluid so received into said vanes at another such boundary.
- 75 16. A turbine comprising in combination stationary elements co-acting with rotating vanes fractionally to convert the thermal energy of the working fluid into useful work, said stationary elements only partly extending over said rotating vanes and terminating in short end blockings to form impingement zone or zones, and means for receiving working fluid from said rotating vanes when passing between adjacent blockings at one impingement zone boundary and for delivering the fluid so received into said vanes on their passage between adjacent blockings at another such boundary.
- 80 17. A turbine comprising in combination stationary elements co-acting with rotating vanes, fractionally to convert the thermal

energy, passages adapted to receive working fluid from the working blades at one impingement zone boundary and to deliver the fluid so received into the blades at another such boundary, said passages at their receiving ends being expanded and at their delivery ends being restricted in cross sectional area, said ends being inclined in the direction of rotation of the working blades.

85 13. In combination with a turbine having partial impingement of the working blades with fractional conversion of the pressure energy of the working fluid into kinetic energy, passages adapted to receive working fluid from said working blades on one side of an impingement zone and to deliver the same into the working blades on the other side of said zone, said passages at their receiving ends being expanded and at their delivery ends being restricted in cross sectional area, said ends being inclined in the direction of rotation of the working blades.

90 14. In combination with a turbine having partial impingement with fractional conversion of the pressure energy of the working fluid into kinetic energy, short end blockings on each side of an impingement zone, passages adapted to receive working fluid from said blades when passing between one set of said blockings, and to deliver the same into said blades on their passage through another set of such blockings, said passages at their receiving ends being expanded and at their delivery ends being restricted in cross sectional area, said ends being inclined in the direction of rotation of the working blades.

95 15. A turbine comprising in combination stationary elements co-acting with rotating vanes fractionally to convert the thermal energy of the working fluid into useful work, said stationary elements only partly extending over said rotating vanes to form impingement zone or zones, and means for receiving working fluid from said rotating vanes at one impingement zone boundary and for delivering the fluid so received into said vanes at another such boundary.

100 16. A turbine comprising in combination stationary elements co-acting with rotating vanes fractionally to convert the thermal energy of the working fluid into useful work, said stationary elements only partly extending over said rotating vanes and terminating in short end blockings to form impingement zone or zones, and means for receiving working fluid from said rotating vanes when passing between adjacent blockings at one impingement zone boundary and for delivering the fluid so received into said vanes on their passage between adjacent blockings at another such boundary.

105 17. A turbine comprising in combination stationary elements co-acting with rotating vanes, fractionally to convert the thermal

energy of the working fluid into useful work, said stationary elements only partly extending over said rotating vanes and terminating in short end blockings to form impingement zone or zones, passages connecting the spaces between the short end blockings on one side of an impingement zone with the spaces between adjacent similar blockings on the other side of this zone.

18. A turbine comprising in combination stationary elements co-acting with rotating vanes, fractionally to convert the thermal energy of the working fluid into useful work, said stationary elements only partly extending over said rotating vanes and terminating in short end blockings to form impingement zone or zones, passages connecting the spaces between the short end blockings on one side of an impingement zone with the spaces between adjacent similar blockings on the other side of this zone, said passages at their receiving ends being expanded and at their delivery ends being restricted in cross sectional area, said ends being inclined in the direction of rotation of the working blades.

19. A turbine comprising in combination stationary elements co-acting with rotating vanes fractionally to convert the thermal energy of the working fluid into useful work, said stationary elements only partly extending over said rotating vanes and terminating in short end blockings to form impingement zone or zones, a casing for said turbine, a member carried by said casing and on which said stationary elements are mounted, passages in said member connecting the spaces between adjacent short end blockings at one impingement zone boundary, with the spaces between similar blockings at another such boundary.

20. A turbine comprising in combination stationary elements co-acting with rotating vanes fractionally to convert the thermal energy of the working fluid into useful work, said stationary elements only partly extending over said rotating vanes and terminating in short end blockings to form impingement zone or zones, a casing for said turbine, a member carried by said casing and on which said stationary elements are mounted, passages in said member connecting the spaces between adjacent short end blockings at one impingement zone boundary, with the spaces between similar blockings at another such boundary, said passages at their receiving ends being expanded and at their delivery ends being restricted in cross sectional area, said ends being inclined in the direction of rotation of the working blades.

21. A turbine comprising in combination stationary elements co-acting with rotating vanes fractionally to convert the thermal energy of the working fluid into useful work,

said stationary elements only partly extending over said rotating vanes and terminating in short end blockings to form impingement zone or zones, a casing for said turbine, passages in said casing connecting the spaces between adjacent blockings at one impingement zone boundary with the spaces between similar blockings at another such boundary.

22. A turbine comprising in combination stationary elements co-acting with rotating vanes fractionally to convert the thermal energy of the working fluid into useful work, said stationary elements only partly extending over said rotating vanes and terminating in short end blockings to form impingement zone or zones, a casing for said turbine, passages in said casing connecting the spaces between adjacent blockings at one impingement zone boundary with the spaces between similar blockings at another such boundary, said passages at their receiving ends being expanded and at their delivery ends being restricted in cross sectional area, said ends being also inclined in the direction of rotation of the working blades.

23. A turbine comprising in combination stationary elements co-acting with rotating vanes, fractionally to convert the thermal energy of the working fluid into useful work, said stationary elements only partly extending over said rotating vanes and terminating in short end blockings to form impingement zone or zones, a casing for said turbine, a member attached to said casing on the inner surface of the latter and on which said stationary elements are mounted, passages connecting the spaces between adjacent short end blockings at one impingement zone boundary with the space between similar blockings at another such boundary, said passages being formed as grooves in said casing and closed by said member.

24. A turbine comprising in combination stationary elements co-acting with rotating vanes, fractionally to convert the thermal energy of the working fluid into useful work, said stationary elements only partly extending over said rotating vanes and terminating in short end blockings to form impingement zone or zones, a casing for said turbine, a member attached to said casing on the inner surface of the latter and on which said stationary elements are mounted, passages connecting the spaces between adjacent short end blockings at one impingement zone boundary with the space between similar blockings at another such boundary, said passages being formed within said member, and at their receiving ends being expanded and at their delivery ends being restricted in cross sectional area, said ends being inclined in the direction of rotation of the working blades.

25. A turbine comprising in combination within a chamber, stationary elements co-

acting with rotating vanes, fractionally to convert the thermal energy of the working fluid to useful work, said stationary elements only partly extending over said rotating vanes and terminating in short end blockings to form impingement zone or zones, in which the pressure of the working fluid is fractionally decreased so that a varying degree of pressure difference exists between the fluid at the different points in said zone or zones and the fluid in said chamber, passages connecting the spaces between the short end blockings at one impingement zone boundary with the spaces between similar

blockings at another such boundary, the number of such passages opening into each of said spaces varying in accordance with the degree of pressure difference existing between this part of said impingement zone or zones and said chamber. 15
